UNITED STATES PATENT OFFICE.

GEORGE GERENDA, OF DUQUESNE, PENNSYLVANIA.

BILLIARD CUE.

Application filed June 23, 1925. Serial No. 39,027.

To all whom it may concern:

Be it known that I, GEORGE GERENDA, a citizen of the United States, and a resident of Duquesne, in the county of Allegheny and State of Pennsylvania, have invented a new and useful Improvement in Billiard Cues, of which the following is a specification.

This invention relates to tips for billiard cues.

The objects of the invention are to provide a new form of attachment for the resilient tips of billiard cues; particularly to make the tip easily removable and renewable, and at the same time to so support and hold the removable tip as to prevent its chipping and splitting. Other uses and advantages will be apparent to those familiar with such devices, from a consideration of the following specification, and from the drawings.

Fig. 1 shows a billiard cue equipped with the removable tip hereinafter described, and Fig. 2 is an enlarged longitudinal central section through the tip and a part of the cue to which the tip is attached.

Cues used in playing billiards and pool and especially those used in public pool rooms, where they are given a large amount of usage, and particularly used by careless and unskilled players, are a source of continual and considerable expense in the matter of renewing the resilient tips, and of keeping the tips in good condition. I do not claim to be the first to provide a removable or renewable tip for cues. My invention resides in the improved arrangement, form, and combination of the parts herein-after referred to.

In the drawings, an ordinary billiard cue shaft 1 is illustrated. The end of this is cut down to form a shoulder 2, with a cylindrical terminal extension 3, adapted to receive a cylindrical ferrule or ring 4, to be retained thereon by frictional contact. For that purpose the neck 3 of the cue is preferably made with a very slight taper, and of such size that it fits into the rear bore of the ferrule 4 with a tight, but reusable frictional engagement.

At the forward end of the ferrule a larger bore 8 is provided, forming an internally tapered shoulder 5, a cylindrical portion 6, and a terminal inner beveled off portion 6a.

A resilient tip T of any suitable composition is adapted to fit into the open end of the

ferrule 4. This tip comprises an enlarged head portion 10, an intermediate frustro-conical portion 11, and a substantially cylindrical base portion 12. This latter base portion is adapted to fit tightly in the smaller bore 7 of the ferrule, and to retain the tip by frictional engagement. The tapered portion 11 of the tip extends from the inner corner of the shoulder 5 to the inner beveled terminal portion 6a of the ferrule, and bears against each. The intermediate portion of the tip 11 bridges between the two contact portions referred to, and is not intended to contact with the inner wall of the bore 8, except at the outer edge thereof, as illustrated.

The head portion 10 of the tip extends laterally even with or slightly beyond the line of the outer surface of the ferrule 4, so that there is no chance of the metal edge of the ferrule coming in contact with the balls during play. The cylindrical portion 12 fits tightly into the bore 7 of the ferrule and retains the tip in place under all normal conditions. The beveled terminal portion 6a of the ferrule contacts with the tip immediately behind the head thereof, and substantially reinforces the head part of the tip, preventing its edges from breaking off or splitting during play. At the same time this bounding portion 6a of the ferrule retains the tip in true position, and reinforces the striking head thereof.

The tips T when worn out or spoiled in any way may be readily replaced with new ones.

The whole device is very simple, easily manufactured, and requires no tools for attachment or detachment. Standard cues may be fitted with these removable tips by simply turning down the ends to form the necks 3. The ferrules 4 are not affected by use, are interchangeable, and are practically indestructible.

I claim:

1. In a billiard cue, the combination of a shaft, a cylindrical ferrule adapted to fit on the end of the shaft, said ferrule having two axially aligned bores of different diameter therein, the larger bore being at the forward end of the ferrule and having a terminal flaring portion, the shaft having a terminal extension adapted to make frictional engagement with the smaller bore of the ferrule, and a resilient tip having a cylindrical base adapted to make frictional engagement

with the forward end of the smaller bore of the ferrule and an enlarged head adapted to seat in the flaring forward end of the larger bore of the ferrule.

5. 2. The combination in a billiard cue of a wooden shaft, a metal ferrule adapted to be retained on the forward end thereof, said ferrule having an open flaring end and a double diameter bore therethrough, and a 10 resilient tip having a cylindrical base portion adapted to fit into the smaller bore of the ferrule, and an enlarged head portion adapted to bear against the flaring forward edge of the ferrule.

- 15 3. The combination in a billiard cue of a

shaft, a terminal ferrule for the shaft, said ferrule having axially aligned bores of different diameters, the larger bore being at the forward end, and a terminal resilient tip 20 adapted to be carried by the ferrule, said tip carrying a substantially cylindrical base portion adapted to fit into the smaller bore of the ferrule, a substantially frusto-conical portion beyond the base of the tip, and an enlarged head portion beyond said frusto-conical portion, said head portion being adapted to seat upon the terminal edge 25 of the ferrule.

In testimony whereof, I sign my name.

GEORGE GERENDA.
